CLAIM

The ornamental design for a faucet spout, as shown and described.

DESCRIPTION

FIG. 1 is a front view of a faucet spout showing my design;
FIG. 2 is a back view thereof;
FIG. 3 is a left side view thereof;
FIG. 4 is a right side view thereof;
FIG. 5 is a top view thereof;
FIG. 6 is a bottom view thereof; and,
FIG. 7 is side view of the faucet spout attached to a conduit.
The dashed lines in FIG. 7 depict unclaimed portions of the
faucet spout as being used. The dashed lines form no part of
the claimed design.
